UNITED STATES PATENT OFFICE.

LEWIS L. IVERSON, OF DECORAH, IOWA.

IMPROVEMENT IN SIDE-HILL PLOWS.

Specification forming part of Letters Patent No. 157,130, dated November 24, 1874; application filed August 25, 1874.

To all whom it may concern:

Be it known that I, LEWIS L. IVERSON, of Decorah, in the county of Winneshiek and State of Iowa, have invented a new and valuable Improvement in Double Plows; and I do hereby declare that the following is a full, clear, and exact description of the construction and operation of the same, reference being had to the annexed drawings making a part of this specification, and to the letters and figures of reference marked thereon.

Figures 1 and 2 of the drawings are representations of side views of my double plow. Fig. 3 is a plan view, Fig. 4 is a rear view, and Fig. 5 is a detail view, of the same.

This invention has relation to double reversible hill-side plows wherein two complete mold-board plows are connected to or formed on a single inclined standard, which can be turned in the beam for bringing either plow into operation at pleasure.

The improvements which I have made consist mainly in a spring - stay at the rear end of the plow-beam, which will receive either one of the plow-points and sustain the plows in the desired position for operation, at the same time allowing the plows to be readily adjusted. It also consists in a holding-down loop, in combination with the stay at the rear end of the plow-beam for resisting shocks while plowing stony land.

In the annexed drawings, A designates the beam of the plow, and B B are the handles thereof. C C are two mold-boards, which are both alike in form, and which are applied to a single land-side plate, D, so as to form two plows, each one being complete in itself, one being intended for right-hand and the other for left-hand plowing. The standard E of these two plows is passed through a metal tube, which is confined in an inclined position in the beam A, and on the upper end of the standard a nut, a, is screwed, as shown in Figs. 1, 2, and 3.

The plows shown by Fig. 5 have hinged

mold-board wings b applied to them, which will greatly shorten the distance between the plow-points, and at the same time give all the breadth of mold-board required. When these hinged wings are employed they will have a cranked arm, c, secured to their upper ends, which arm will be received into a casting on the plow-beam, for the purpose of adjusting the wings properly when the plows are adjusted. At the rear extremity of the plow-beam is a stay-piece, d, having a recess in its bottom to receive the points of the plows. This stay-piece is secured to a spring-plate, S, which is fastened on top of the beam A, and the edges of the stay d are under-beveled, so that when the plows are swung around the point of the rearmost plow will spring up the stay and engage in its recess. In front of the stay-piece d, and rigidly secured to the beam A, is a loop, g, against which the rearmost plow presses when the front plow is in proper position for working. This loop g resists the downward thrusts of the front plow-point in plowing stony land. Lateral displacement of the front plow-point is prevented by means of a brace, e, which is pivoted to the under side of the beam A and hooked into the upper part of the mold-board of the rear plow. This brace is made of two extensible sections, which can be shortened or lengthened for giving more or less land to the working plow.

What I claim as new, and desire to secure by Letters Patent, is—

1. The spring stay-block d, combined with the reversible double plow, substantially as described.

2. The loop g, combined with the reversible double plow, substantially as described.

In testimony that I claim the above I have hereunto subscribed my name in the presence of two witnesses.

LEWIS L. IVERSON.
